DISPENSING DEVICE

Paul I. Schultz and James J. Pelouch, Cleveland,
Ohio, assignors to The United States Air Com-
pressor Company, Cleveland, Ohio, a corpora-
tion of Ohio

Application February 1, 1936, Serial No. 61,982

44 Claims. (Cl. 221—47.1)

Our invention relates, in general, to dispensing devices and more particularly to devices for pumping lubricating oils and greases out of their "original container", and conducting the oil and grease directly from the "original container" to the parts to be lubricated, and also for holding the "original container" from which the contents are being removed.

An object of our invention is to provide a device for holding and supporting an "original container", while the contents are being removed through an opening in the top of the container.

Another object of our invention is to provide a means by which a pumping device may be moved in and out of operative position in respect to the said container with a minimum of effort.

A still further object is to provide a pumping system which is supported in a floating manner in a relative position to a container from which the contents are to be removed.

Another object is to provide a cover for a compartment for the "original container", which cover may be raised and lowered with a minimum of effort.

Another object is to provide weight or lift equalizing means for supporting a pumping device adapted to be lowered into operative position in respect to an "original container".

Still another object is to provide spring suspension means for aiding in the support of a pumping device so that the pumping device is floatably supported above an opening in the "original container" so that the pumping device may be raised and lowered in respect to the opening in the container with relative ease.

Another object is to provide a support or holding member for holding an "original container" and through the side of which the container may be moved without hindrance of the pumping device extending into the container.

A still further object is to provide a device for holding an "original container" of fluid and constructed so that the container may be moved in and out of the compartment of the device through an opening in the side of the compartment, and further so that a pumping device may be lowered into the opening in the top of the container when the container is within the compartment and so that the pumping device may be raised out of the opening in the container when the container is to be moved, to the end that the pumping device will not hinder or limit the movement of the container through the side of the compartment.

Another object of my invention is to provide

a suitable enclosure for an "original container" while the contents of the "original container" are being removed.

A further object of our invention is to provide a compartment for accommodating an "original container", which compartment is entirely lifted up for the removal of the "original container" or the placement of the "original container" under the compartment, and more particularly to provide a system of counter-weights to equalize the weight of the compartment, thus aiding in the raising and lowering of the compartment.

A still further object is to provide a system of counter-weights for aiding in the raising and lowering of the pump plunger into, and out of, the "original container", accommodated in a compartment supporting the pump.

Other objects and a fuller understanding of our invention may be had by referring to the following description and claims taken in combination with the accompanying drawings, in which:

Figure 1 represents a perspective view of our device enclosed in operating position;

Figure 2 represents a perspective view of our device with the door open, the container removed, and the pump raised;

Figure 3 represents a detailed and fragmentary view of the spring suspension parts of which the lifting mechanism is shown in Figure 2;

Figure 4 represents a modified form of the device shown in Figures 2 and 3;

Figure 5 shows in cross sectional view, a positive or pin stop for holding the supporting rods in position;

Figure 6 is a cross-sectional view taken through the line 6—6 of Figure 5;

Figure 7 is a side view of a portion of the device shown in Figure 4;

Figure 8 illustrates another modification of the method of supporting and raising the pumping device in which there are no spring suspension means;

Figure 9 is a view through the line 9—9 of Figure 8;

Figure 10 is a detailed view of the rack and pinion drive of the modification shown in Figure 8 and is taken along the line 10—10;

Figure 11 illustrates another modified form of our device in which there are no supporting and raising means for the pump and cover;

Figure 12 is a side view of another modification of our invention, showing a side view of the pulley and weight arrangement with the compartment down;

Figure 13 illustrates in detail the pulley and weight arrangement of Figure 12;

Figure 14 shows a front view of the modification illustrated in Figure 12, with the compartment in raised position;

Figure 15 illustrates another modification in which the staff standards extend up through the cover of the compartment;

Figure 16 illustrates in detail the pulley arrangement shown in Figure 15.

Referring to Figures 1 and 2, the reference character 11 represents the base or support of our construction. Located centrally of the base 11 is a sump in which a pan 10 is placed for collection of any drippings of fluid which may fall. Securely mounted by screws and bolts or other suitable means to the base 11 is the compartment 13. The compartment 13 as shown is generally constructed of sheet metal and is formed to accommodate a container which is to be placed upon the base 11. The sides of the compartment or holding member 13 are braced by means of the cross braces 12. Upon one side of the compartment or holding member 13 is a door 14 hingedly attached to the compartment 13 by means of the hinge 22.

A cover 15 of a size and shape suitable for covering the top of the compartment 13, sets over the open top of the compartment 13. Mounted approximate to the cover 15 is a pump 16 together with a valve assembly 17 for the pump 16. The pump 16 and the valve assembly 17 are of the conventional type, and together they constitute a pumping device operated by air pressure. The air for operating the pump is brought to the pump through a hose or other conduit not shown. In communication with the pump 16 is a hose 18, which in turn, has connected to it, a grease nozzle 20. The nozzle 20 is of the usual form used for applying lubricants directly to the part to be lubricated. The hose 18 is shown coiled around the pump 16, but when in operation, the nozzle 20 is applied directly to the grease cup or other part into which the lubricant is to be placed.

More of the details of the construction of the device is shown in Figure 2 in which the door 14 extends open and the container removed. Mounted on the base 11 are two slides shown by the reference character 21. In this manner, the container may be slid into, and out of, the compartment 13 upon the slides 21. The door 14 mounted upon the hinge 22 is kept in closed position by means of the complementary parts of the latch 19.

Shown mounted transversely of the compartment or holding member 13 is a cylinder 23, the mounting of which will hereinafter be described in more detailed fashion. The pulleys 29 are mounted on the cylinder 23 and wound around the pulleys 29 is shown the cable 44. At the end, the cable is suitably secured to the supporting rods 47 by means of the fastening 45. The supporting rods 47 are slidably engaged in the sliding member 46 which in turn, is secured to the sides 65 of the compartment 13. The fastening 45 is adjustable so that the cable 44 may be fastened to the rod 47 at a proper position on the cable 44. The view in Figure 2 also shows the inlet member 49 which is in communication with the pump 16 and which extends down through an opening in the cover 15. The valve end of the inlet member 49 is shown by the reference character 50. In this view, the cover 15, the pump 16, and the inlet member 49 are shown raised to its upper limit, so that a container may be freely inserted

or withdrawn from the compartment 13 through the side of the compartment 13 when the door 14 is opened. The view 2a shows the "original container" 81 having an opening 82 in its top. This container 81 is shown sitting beside the compartment 13.

Referring to Figure 3, we show in detail, the parts of the spring suspension means and illustrate the assembly of the parts. Running transversely of the compartment 13 is a shaft 25. Coiled around the shaft 25 is a coil spring 24. On the left side of the view shown in Figure 3, the end of the coil spring 24 is secured to the floating anchor 36 by means of the screw 37. The other end of the coil spring is secured to the anchor member 26 by means of the screw 28. The shaft 25 is secured to the anchor member 26 by means of the left hand screw threads 35 and the outside nut 33. The anchor member 26 is threadably secured to the abutting member 30, which in turn, is screwed to the sides of the compartment 13 through the re-enforcing plate 31 by means of the screws 32.

Enclosing the shaft 25, the coil spring 24, the floating anchor 36, and the anchor member 26 is 23 the cylinder 23. Secured to each end of the cylinder 23 near its ends are the pulleys 29. The pulleys 29 may be secured by any suitable means. We prefer to secure them by the welding shown by the reference character 38. On the left side 30 of the view shown in Figure 3, the floating anchor 36 is shown as being rotatively mounted upon the abutting member 39. The abutting member 39 is secured to the sides of the compartment 13 through the re-enforcing plate 31 by means of the 35 screws 40.

The left end of the cylinder 23 is non-rotatively secured to the floating anchor 36 by means of the screw 37. The right end of the cylinder 23 is mounted upon the floating collar member 27 40 which is free to rotate about the anchor member 26, which anchor member 26 is in turn, secured to the shaft 25.

The brake member 41 is threaded upon the shaft 25 by means of the threads 43. By turning 45 the brake member 41 upon the threads 43, the brake member 41 is forced back and forth upon the shaft 25 so as to form a friction brake against the floating anchor 36 where the two parts meet. The inward action of the brake 41 is also transmitted through the assembled parts 36, 23 and 27 to press the collar member 27 against the abutting member 30. Thus, when the brake member 41 is turned inwardly, it engages the floating anchor 36, thus tending to bind the two parts together, which in turn, tends to bind the floating anchor 36 to the shaft 25, and tends to bind 27 to 30, making an effective braking action. When the anchor 41 is turned outwardly, then the parts are released and free to rotate.

The left end of the shaft 25 has a squared end 42 and is adapted to engage with a wrench not shown, which is used for turning the shaft 25, when adjusting the spring tension of the spring 24 during the assembly. Each end of the shaft 65 25 has openings designated by the same reference character 34 running through to the bearing parts and are adapted to provide access for oil for lubricating these parts.

The parts shown in Figure 3 are assembled and 70 mounted in the following manner: Preparatory to assembling and mounting, a re-enforcing plate 31 is secured in the sides of the compartment 13. The cover 15 is removed prior to the mounting of the parts. The floating anchor 36 is placed in 75

the left end of the cylinder 23, which already has the pulleys 29 welded in place. The coil spring 24 is next placed through the right end of the cylinder 23. It is moved about until the 5 left end of the spring 24 is in proper position upon the floating anchor 36 at which time the screw 31 is inserted so as to firmly engage the left end of the spring 24 to the floating anchor 36. The parts 26, 27 and 30 are next assembled 10 by placing the collar member 27 over the neck of the anchor member 26 and screwing the abutting member 30 down upon the threaded portion of the anchor member 26. The right hand end of the spring 24 is then pulled out of the cylinder 23, the spring being stretched for that purpose. This right hand end of the spring 24 is then secured to the anchor member 26 by means 15 of the screw 28. The floating collar member 27 is fitted inside the end of the cylinder 23. By this assembly, the floating collar member 27 is free to rotate about the anchor member 26.

Again referring to the left hand end, the abutting member 39 is inserted in proper position into the recess shown in the floating anchor 36. 25 It is now seen that the assembled parts are slightly longer than the width of the compartment 13. Therefore, in order to lower the assembled parts into proper position in the compartment 13, the sides of the compartment 13 30 and the re-enforcing plates 31 will have to be slightly bulged outwardly. As is seen in the drawings, the amount which these parts will have to be bulged outward, is about the same as the thickness of the right-hand wall of the compartment 13 plus the thickness of the right-hand 35 re-enforcing plate 31. The assembled parts are then lowered down into the compartment 13 until they are in proper position so as to coincide with the holes already provided through the 40 sides of the compartment 13 and the re-enforcing plates 31. When in this position, the shaft 25 is inserted from the left hand side through the wall of the compartment 13 and pushed through the center opening of the assembled parts so that 45 the floating anchor 36, the spring 24, and the anchor member 26, are all mounted upon the shaft 25. The shaft 25 is secured to the anchor member 26 by threading it upon the left hand screw threads 35. The right hand end of the 50 shaft 25 then extends slightly outwardly of the compartment 13. Threaded to this end by a right hand thread is the nut 33, thus it is seen that the right hand end of the shaft 25 is non-rotatively secured to the anchor member 26, which 55 in turn, is secured to both the right hand end of the coil spring 24 and the abutting member 30. The abutting member 39 is secured to the compartment 13 and re-enforcing plate 31 by the screws 40. However, the screws 32 are not 60 placed in position as yet so the abutting member 30 may still rotate.

The brake member 41 may now be inserted into place over the left hand end of the shaft 25 but is not turned down to braking position. 65 Next the cover 25 with the mounted pump 16 is placed in position. The supporting rods 47 are run down through the sliding member 46. The cover 15 and the mounted pump 16, together with the supporting rods 47, are placed so that 70 the cover and pump rest upon the sides of the compartment 13 and the rods 47 extend down into the compartment. One end of the cable 44 is secured to the pulley 29 so as to readily wind about the pulley. The cable is then extended 75 down and is fastened to the end of the rod 47 by

means of the fastening 45. The fastening 45 is such that the cable 44 may be fastened readily at any point on the cable.

At this point, the coil spring 24 has no tension upon it. Therefore, in order to put proper tension on the coil spring 24 so that it may properly react with the cable 44 and the supporting rods 47, it is necessary that the coil spring be wound up. To do this, a wrench is engaged upon the square end 42 of the shaft 25 and the wrench 10 rotated. Since the pulleys are held in position by movement of the cables 44, the rotation of the shaft 25 causes the right hand end of the coil spring to rotate about the shaft 25, while the left hand end of the coil spring is held stationary. 15 Also the abutting member 30 will rotate just as the anchor member 26 rotates, as at this point, the screws 32 have not yet been inserted. In this manner, the coil spring 24 is wound up to the proper tension, that is, until the action of the 20 spring in causing a winding action on the pulleys 29, a pulling action on the cables 44, and a raising action on the rods 47, exerts such a force upon the cover and pump as to cause them to tend to raise. This lift equalizing combination 25 in effect causes the cover and pump to "float" so that little or no effort is necessary to raise them. When the desired tension is thus obtained, the wrench is no longer turned and the right end of the shaft is anchored by fastening the abutting 30 member 30 to the compartment 13 by means of screwing in the screws 32 in position. These screws 32 thus anchor the right end of the shaft 25 and the right hand end of the coil spring 24 35 against rotation.

It is therefore, seen that when the weight of the cover 15, together with the mounted pump 16, exerts its force upon the supporting rods 47, the coil spring 24 acts as a weight or lift equalizing means and tends to force the supporting 40 rods 47 upwardly through the agency of the connected cables 44, thus tending to counter-balance the weight of the cover 15 with the parts mounted thereon.

To illustrate, the operation of our device, the following steps of use are stated: The brake 41 is turned so as to be in a released position. The cover 15 is raised upwardly either entirely by reason of the spring action or by using a minimum of manual effort to aid the action of the 50 spring. It is thus seen that in this position, the inlet member 49 of the pump is raised out of operating position. The door 14 of the compartment 13 is opened, and the "original container" 81 full of a fluid of any viscosity, such as oil or 55 grease, is placed through the open door into the compartment 13. The cover 15 with the parts mounted thereon may be securely locked in raised position at this time by the turning of the brake 41. The cover 15 and the pump mounted thereon, are then lowered by either releasing the 60 brake 41 or by using a minimum of manual effort by pulling the cover 15 downwards. The inlet member 49 is thus inserted through the opening 65 82 of the "original container" 81 so that the end 50 of the inlet member 49 is approximate to the bottom of the container 81. The door 14 may then be closed and the device is ready for operation, the container being entirely enclosed as is shown in Figure 1.

To put in a different container so as to replenish the supply of fluid, the operation is reversed so as to raise the inlet member 49 out of the container, thus removing any hindrance from the moving of the container 81 out through the 75

side door of the compartment or holding member 13.

In Figure 4, we show a modified form of our invention in which the supporting rods are eliminated and the cover 15 with the parts mounted thereon are supported by means of the inlet member 54. The pump on the cover 15 is not shown in Figure 4 as it is the same as in Figure 2. The pulleys 52 are mounted centrally of the cylinder 51 which cylinder 51, with its enclosed parts, is similar to cylinder 23 of Figure 3 with its enclosed parts. The assembling and mounting of the parts in this case is similar to that shown and described for the preferred form shown in Figure 3. Secured to the pulleys 52 and wound around them are the cables 53 which have their lower ends attached to the ears 56 of the end portion 55 of the inlet member 54. To guide the inlet member 54, we provide a guide member 58 which is secured to the brace 57, which in turn, is mounted upon the compartment 13. A set screw 59 is provided in the guide member 58 so that the plunger 54 may be secured at any elevation desired. Thus it is to be seen that the tension of the coil spring 25 within the cylinder 51 will cause the pulleys to turn so as to exert a force upon the cables 53. The action of the coil spring thus tends to pull the inlet member 54 upwardly so as to raise both the inlet member 54, and the cover 15, together with the pump mounted thereon. The operation of this modified form of our invention is the same as that used in the preferred form as illustrated in Figures 2 and 3.

Figure 7 shows a side view of the inlet member 54 and the pulley 52 of Figure 4 and illustrates the correlation of the parts shown.

In Figures 5 and 6, we show a modified form of braking the supporting rods 47 of the preferred form. Referring to Figure 5, the supporting rod 47 is slidably engaged in the slide member 46. The slide member 46 has a hole 62. The supporting rod 47 has a series of holes, two of which are shown as hole 61 and hole 60. To positively keep one of these holes in the supporting rod 47 in alignment with the hole 62 of the slide member 46, we provide a pin member 63, which is suitably mounted to the compartment 13 by means of the housing 64. To keep the pin member 63 directed inwardly, we provide a small coil spring 65. It is observed that when the pin member 63 is manually pulled outwardly, the supporting rod is free to slide up and down within the slide member 46, but that when the hole 62 coincides with one of the holes in the supporting rod 47, and the pin member 63 is released, the supporting rod 47 is locked against sliding movement. The cable 44 is fastened to the end of the supporting rod 47 by means of the fastening 45 which is adjustable so that any desired position on the cable may be adjustably clamped at 45.

Figure 6 shows a view through the line 6—6 of Figure 5 and shows in detail, the relationship of the parts 46, 63, and 47 as seen from above. This view further shows how the slide member 47 is bolted to the sides of the compartment 13 and how the supporting rod 47 is slidably engaged within the slide member 46.

Figure 8 shows another modification of our invention in which there is no weight or lift equalizing means or no spring tension means for aiding the supporting of the cover and pump. In this modification, the supporting rods 70 are provided with teeth to form a rack, which teeth engage with the teeth of the pinions 67. The pin-

ions 67 are mounted upon the shaft 66 which, in turn, is mounted transversely of the compartment in openings provided therein. Securing the right hand end of the shaft 66 and acting as a bearing therefor, is a bearing member 68. Mounted on the left hand end of the shaft just outside of the compartment is the bearing 72. The pinions 67 are prevented from rotating about the shaft 66 by means of the pins 69, inserted in the slots of the shaft.

The supporting rods 70 are slidably engaged in slide members 71, which slide members are not shown in Figure 8, but are shown in Figure 10. In order to raise or lower the supporting rods 70, the shaft 66 and the pinions 67 are rotated by turning the crank-arm 77 which is provided with a handle 78. It is apparent that by turning the crank 77 in one direction, the supporting rods 70 will be raised, thus raising the cover and pump and by turning in another direction, the supporting rods 70 will be lowered, thus lowering the cover and pump.

In order to lock the shaft and pinion from moving but in one direction, as the cover and pump is raised, we provide a ratchet lock 75. This ratchet lock is particularly illustrated in Figure 9 which is a view shown through the line 9—9 of Figure 8. The ratchet 75 is pivotally mounted on the pin 76 and is held down by a spring 74 secured at its lower end to a pin 73. The end of the ratchet 75 is arranged to catch upon the stop pin 79 when the crank arm 77 turns in one direction but to slide over and past the stop pin 79 when going in another direction. In this manner, the shaft and gears may be locked against downward movement when this ratchet 75 is in operating position. To lower the supporting rods 70, it will then be necessary to lift the ratchet 75 up out of operating position so that it will not catch on the stop pin 79.

In Figure 10, we show a side view of the rack and pinion drive of the modification shown in Figure 8, which shows a view taken along the line 10—10 of Figure 8. This view shows the supporting rod 70 slidably engaged within the slide member 71. The teeth of the supporting rod 70 engage the teeth of the pinion 67 which is mounted upon the shaft 66 and non-rotatively secured thereto by the pin 69. The rack and pinion drive illustrated shows that the turning of the pinion 67 causes a longitudinal movement of the supporting rod 70.

In Figure 11, we illustrate another modification of our invention, in which we provide no supporting or raising means for the cover and parts mounted thereon. In this modification, the cover and parts mounted thereon are manually raised and lowered in and out of the container, and the weight of the cover and parts mounted thereon rests upon the sides of the compartment 13. In the view illustrated, the device is shown when not in use. In order to provide a safe place for the pump and inlet member, when not in operating position, we provide a cross brace 80 in one corner of the compartment 13. This brace 80 properly supports the inlet member 49 and safely holds the device in a convenient place. The container is inserted within the compartment. The cover, pump, and inlet member are raised and lowered down again centrally of the compartment into the opening of the container and is ready for use. To take care of any drippings from the plunger, we provide a sump in the base 11 in which is placed a pan 9 under the plunger.

In Figure 12, we show another modification of 75

our invention, in which the cover 15 is permanently attached by any suitable means, such as screws or welding, to the sides of the compartment 13 and the whole compartment is raised and lowered. The pump 16 is shown as mounted on the cover 15. When in the lowered position, the weight of the compartment 13 and its dependent parts rests upon the base 11. Firmly mounted within the compartment 13 upon the base 11 on each side thereof is an upright standard 90 permanently secured to the base 11 by means of the flange support 91 screwed to the base 11. The upper end of the upright standard 90 is split and within the split portion is mounted a pulley 97 in a slightly offset position, by means of the pin 98. One end of the cable 95 is secured to a counter-weight 100. Slidably mounted upon the standard 90 is a guide member 92 and upon the guide member 92 is a hook portion 94, to which the lower end of the cable 95 is attached. The sides of the compartment 13 are firmly attached to the guide member 92 by means of the screws 93 which are inserted from outside the compartment 13 through holes in the sides of the compartment 13 and into the guide member 92. It is thus seen that the guide member 92 is free to slide up and down the standard 90. By being attached to the compartment 13, the guide member 92 carries the compartment 13 and its depending parts with it. It is therefore seen that the counter-weight 100, being attached to the cable 95 which is swinging over the pulley 97, tends to raise the guide member 92, and in turn, tends to raise the compartment 13. In order to prevent the guide member 92 from ascending on the standard 90, so far as to jam against the pulley 97, we provide a stop 101 secured in the standard 90 at a point just below the pulley 97. By this means, the holding compartment 13 may be raised and lowered with the assistance of this counter-weight system. Just as in the preferred form shown in Figure 2, this greatly facilitates the moving of the "original container" 81 off and on its place on the base 11 in that the inlet member 49, being carried by the compartment 13, is raised and lowered in and out of the opening 82 in the "original container" 81 with a minimum of effort.

Figure 13 shows in more detail, the mounting 50 of the counter-weight system and shows the counter-weight 100 attached to the end of the cable 95 by means of the cable clamp 99, and shows the lower end of the cable attached to the hook 94 by means of forming a loop of the cable 55 with the aid of the cable clamp member 98. The standard 90 and the cable 95 are shown as broken, and the parts illustrated show the complete assembly. The stop 101 is mounted transversely of the standard 90 near the pulley 97 so as to prevent the guide member 92 from jamming against the pulley 97. The screws 93 are shown in the guide member 92 which screws are used for attaching the sides of the compartment 13 to the guide member 92. The pulley 97 is slightly set off so that the counter-weight 100 will not interfere with the movement of the guide member 92.

Figure 14 shows the same modification as is shown in Figure 12 but represents a front view of the device with the compartment 13 in a raised position. The inlet member 49 and its end 50 is shown as being raised up along with the compartment 13 so that the inlet member 49 is completely out of the opening 82 in the "original container" 81. With the compartment 13 being 75 in a raised position, the counter-weights 100 are

shown as being down near the base 11 while the guide members 92 are raised so as to be near the pulleys 112. In order to prevent the guide member 92 from sliding too high upon the standard 90 and jamming against the pulley 112, we provide a stop 101 which blocks the guide member 92 from ascending past the stop. When in the position shown in Figure 14, the "original container" 81 may be slid sideways in and out of its position on the base 11. Thus, the same purpose is served 10 as in the preferred form shown in Figure 2 in that the inlet member 49 may be easily raised out of the opening 82 so as not to prevent the sideways movement of the "original container" 81.

In Figure 15, we illustrate still another modification somewhat similar to the modification shown in Figures 12 and 14. In this view, the long upright standards are represented by the reference character 105. These standards 105 extend up through holes 106 in the cover 15 and 20 are mounted firmly upon the base 11 by means of the flanged supports 107. The holes 106 are large enough to permit the compartment 13 and cover 15 to slide up and down the standards 105, by reason of the standards 105 sliding through 25 the holes 106. In this modification, we use two guide members, the lower members being represented by the reference character 108 and the upper guide member being represented by the reference character 110. The guide members 108 30 and 110 are each firmly secured to the sides of the compartment 13 by means of the screws 109. Just below the upper guide member is shown the pulleys 112 which are mounted within a split portion of the standards 105 by means of the pins 35 115. To prevent the lower guide member 108 from jamming against the pulleys 112, we provide a stop 102 set transversely in the standard 105. A cable 113 has one end attached to the lower guide member 108 in a similar manner to 40 that shown in Figure 13. The other end of the cable is swung over the pulley 112 and attached to the counter-weight 111 in a similar fashion as is shown in Figure 13. The upper two ends of the standards 105 are joined together by the sign 45 member 114 which acts as a brace for the two standards 105 and which is also adapted to bear an advertising sign. The sign member 114 may be attached to the standards 105 by screws or welding or other suitable means. 50

To show the detail of the mounting of the pulley 112 within the split portion of the standard 105, we show the parts in Figure 16 in which the pulley 112 is set within the split portion of the standard 105 and is set off slightly from the 55 center of the standard so as to allow additional leeway for the counterweight. The pulley 112 is rotatably secured by means of the pin 115 and the cable 113 swung over the pulley 112.

To operate the modification shown in Figure 60 15, the compartment 13 and its dependent parts are manually raised. The effort required to raise the compartment 13 is minimized by reason of the assistance of the counter-weight system provided so all or a part of the weight of the compartment 13 and its dependent parts is equalized by this counter-weight system. When the compartment 13 is raised, then it is seen that the inlet member 49 is also raised up out of the "original 70 container" 81 so that the "original container" 81 may be slid sideways in and out from under the compartment 13. The use of the longer standards 105 and the two sets of guide members 108 75 and 110 assist in the raising of the compartment 75

18 in a perpendicular manner and to more readily support the compartment 18 while raised.

The illustrations shown are especially adapted for use in dispensing grease, oil, or other lubricant capable of being pumped or forced through a conduit. However, it is to be understood that this device may be used for dispensing any fluid capable of being pumped or forced through a conduit regardless of its viscosity.

10 The great advantage resulting from the use of our invention is apparent from an inspection of this device. For example, when our device is used in dispensing grease for lubricating automobiles, the grease need not be taken out of the 15 "original container" and placed in another container, as would ordinarily be done. By using our device, the grease may be transmitted directly from the "original container" through the pumping device and conduit right to the mechanical 20 parts to be greased. A further advantage is seen in that the "original container" need not be lifted up and dropped down into a compartment, but may be slid sideways into the enclosing compartment. Still another advantage is that the 25 pump and its plunger can be lifted out of the container manually with a minimum of effort as the weight of the pump and its plunger is wholly or partially counter-balanced by the tension of the coil spring, or by the aid of counter-weights, 30 or by the rack and pinion drive. This greatly facilitates the changing of the container in the compartment, as so little effort is required to withdraw the pump plunger from the opening in the top of the container.

35 Although we have described our invention with a certain degree of particularity, it is understood that the present disclosure has been made only by way of example and that numerous changes in the details of construction and the combination 40 and arrangement of parts may be resorted to without departing from the spirit and the scope of the invention as hereinafter claimed.

We claim as our invention:

1. The combination of a support for a container 45 of fluid, said container having an opening in the top of the container, the said support having a base and a side member carried by the base, said side member being adapted to hold the said container on the said base, the said side member 50 having a side through which the container may be moved, a pumping device carried by the said support for removing the fluid in the container, said pumping device having an inlet member adapted to be lowered through the opening in the 55 top of the container into operative position in the said container and adapted to be raised up from the opening in the container out of operative position so that the said container may be moved sideways through the side of the support, and 60 lift equalizing means carried by said support for counterbalancing part of the weight of said inlet member so that said inlet member may be raised and lowered through the opening in the top of the container with a minimum of auxiliary effort 65 when the said container is moved in and out of its position on the support.

2. The combination of a support for a container of fluid, said container having an opening in its top for the removal of the fluid, a pump carried 70 by the said support for removing said fluid, said pump having an inlet member for inserting through said opening into the container, means for supporting said pump over the container, means for raising the pump so that said inlet member is withdrawn from the container, and

weight equalizing means carried by said support for contributing to the support of the pump.

3. A device for dispensing fluid from a container through an opening in the top of the container comprising, in combination, a holding member for accommodating said container, said holding member having a side portion through which the container may be moved, a top cover for said holding member, a pump mounted on said cover, the said pump having an inlet member extending through the said cover and adapted to be inserted through the opening of the container into said container, a supporting rod means attached to said cover and slidably engaged to the holding member, spring tension means carried by said holding member, and connecting means between said supporting rod means and said spring tension means, the combination of the holding member, the pump, the connecting means, and the spring tension means being such that the inlet member of the pump may be lowered and raised in respect to said container with the aid of said spring tension means and so as to permit the container to be moved through the side of the holding member by raising the inlet member out of the opening in the container.

4. A device for dispensing fluid from a container through an opening in the top of the container comprising, in combination, a holding member for accommodating said container, said holding member having a side portion through which the container may be moved, a top cover for said holding member, a pump mounted on said cover, the said pump having an inlet member extending through the said cover and adapted to be inserted through the opening of the container into said container, supporting means for said pump and inlet member, spring tension means carried by said holding member and connecting means between said supporting means and said spring tension means, the combination of the holding member, the pump, the connecting means, and the spring tension means being such that the inlet member of the pump may be lowered and raised in respect to said container with the aid of said tension means and so as to permit the container to be moved through the side of the holding member by raising the inlet member out of the opening in the container.

5. A device for dispensing fluid from a container through an opening in the top of the container comprising, in combination, a holding member for accommodating said container, said holding member having a side portion through which the container may be moved, a top cover for said holding member, a pump mounted on said cover, the said pump having an inlet member extending through the said cover and adapted to be inserted through the opening of the container into said container, supporting means for said pump and inlet member, a coil spring having one end anchored to said holding member, a cable connecting the other end of said spring to the said supporting means, a reel for said cable, said spring and cable being adapted to contribute toward the support of said supporting means, the combination of the holding member, the pump, and the spring being such that the inlet member of the pump may be lowered and raised in respect to said container with the aid of said coil spring and so as to permit the container to be moved through the side of the holding member by raising the inlet member out of the opening in the container.

6. A device for dispensing fluid from a con- 75

- 5 tainer through an opening in the top of the container comprising, in combination, a holding member for accommodating said container, said holding member having a side portion through which the container may be moved, a top cover for said holding member, a pump mounted over said cover, the said pump having an inlet member extending through the said cover and adapted to be inserted through the opening of the container into said container, a supporting rod for supporting said pump and inlet member, said supporting rod being slidably engaged to said holding member, lift equalizing means mounted on said holding member, connecting means between said lift equalizing means and said supporting rod, the said lift equalizing means being adapted to contribute to the support of said pump and inlet member so as to aid in the withdrawal of said inlet member from the opening 10 in the top of the container, and friction braking means carried by said holding member, said friction braking means being adapted to hold said inlet member at a pre-determined elevation upon the operation of said friction braking means.
- 15 7. A device for dispensing fluid from a container through an opening, in the top of the container comprising, in combination, a holding member for accommodating said container, said holding member having a side portion through which the container may be moved, a top cover for said holding member, a pump mounted over said cover, the said pump having an inlet member extending through the said cover and adapted to be inserted through the opening of the container into said container, a supporting rod for supporting said pump and inlet member, said supporting rod being slidably engaged to said holding member, lift equalizing means mounted on said holding member, connecting means between said lift equalizing means and said supporting rod, the said lift equalizing means being adapted to contribute to the support of said pump and inlet member so as to aid in the withdrawal of said inlet member from the opening in the top of the container, and stop means for locking said supporting rod against movement relative to said holding member.
- 20 8. A device for dispensing fluid from a container through an opening in the top of the container comprising, in combination, a holding member for accommodating said container, said holding member having a base and a side member carried by the base, said side member being adapted to embrace the said container on the base, the said side member having a side portion through which said container may be moved, a top cover for said holding member, a pump supported by said holding member, the said pump having an inlet member being adapted to be inserted through the opening of the container into said container, and means carried by said holding member for raising said pump and inlet member, the said inlet member being adapted to be raised out of said container so that the container may be moved through the side portion of said holding member, and adapted to be lowered into said container so that fluid therein may be removed.
- 25 9. A device for dispensing fluid from a container through an opening in the top of the container comprising, in combination, a holding member for accommodating said container, said holding member having a base and a side member carried by said base, said side member having a side portion through which said con-

tainer may be moved, a top cover for said holding member, a pump supported by said side member, the said pump having an inlet member extending downwardly and adapted to be inserted through the opening of the container into said container, and means carried by said holding member for lowering and raising said inlet member into and out of the opening in the top of the container so that the inlet member may be lowered into the container for pumping the fluid therefrom and raised from the container so that the container may be moved through the side portion of the holding member.

10. A device for dispensing fluid from a container through an opening in the top of the container comprising, in combination, a holding member for accommodating said container, said holding member having a side portion through which said container may be moved, a top cover for said holding member, a pump supported by said holding member, the said pump having an inlet member extending downwardly and adapted to be inserted through the opening of the container into said container, means for lowering and raising said inlet member into and out of the opening in the top of the container so that the inlet member may be lowered into the container for pumping the fluid therefrom and raised from the container so that the container may be moved through the side portion of the holding member, and ratchet means carried by said holding member and engaging said lowering and raising means, said ratchet means being adapted to permit movement of the inlet member in one direction and to prevent movement of the inlet member in the opposite direction.

11. A device for dispensing fluid from a container through an opening in the top of the container comprising, in combination, a holding member for accommodating said container, said holding member having a side portion through which said container may be moved, a top cover for said holding member, a pump supported by said holding member, the said pump having an inlet member extending downwardly through and fastened to said top cover and adapted to be inserted through the opening of the container into said container, the said inlet member being adapted to be raised out of said container so that the container may be moved through the side portion of said holding member and adapted to be lowered into said container so that the fluid therein may be removed, and means carried by said holding member for holding said inlet member and cover in upright position when said inlet member is withdrawn from said container and said cover is removed from said holding member, said means being mounted below said cover.

12. A device for dispensing fluid from a container through an opening in the top of the container comprising, in combination, a holding member for accommodating said container, said holding member having a side portion through which said container may be moved, a top cover for said holding member, a pump supported by said holding member, the said pump having an inlet member extending downwardly through said cover and adapted to be inserted through the opening of the container into said container, a rack member slidably engaged to the holding member for supporting said pump and inlet member, a pinion engaging said rack member and being rotatably mounted upon said holding member, and means for rotating said pinion so as to 75

move the said rack member and to raise the inlet member out of operating position above the container and to lower the inlet member into operating position within the container.

- 5 13. A device for dispensing fluid from a container through an opening in the top of the container comprising, in combination, a holding member for accommodating said container, said holding member having a side portion through 10 which said container may be moved, a top cover for said holding member, a pump supported by said holding member, the said pump having an inlet member extending through said cover and adapted to be inserted through the opening of the 15 container into said container, spring tension means mounted to said holding member, a pulley mounted upon and responsive to said tension means, flexible connecting means connecting said pulley and said inlet member so that the action 20 of the spring tension means contributes to the support of said inlet member and aids in the raising of the inlet member out of the opening in the top of the container, and a guide member slidably engaging said inlet member for guiding 25 its movement.

14. A device for dispensing fluid from a container through an opening in the top of the container comprising, in combination, a holding member for accommodating said container, said 30 holding member having a side portion through which said container may be moved, a top cover for said holding member, a pump supported by said holding member, the said pump having an inlet member extending through said cover and adapted to be inserted through the opening of the 35 container into said container, and a coil spring carried by said holding member having one end anchored to the holding member and the other end anchored to the said inlet member 40 and adapted to exert an upward force upon said inlet member.

15. A device for dispensing fluid from a container through an opening in the top of the container comprising, in combination, a compartment for accommodating said container, a base for said compartment, said base being adapted to support said container within said compartment, a pump supported by said compartment, the said pump having an inlet member extending 45 downwardly into said compartment and being adapted to be lowered through the opening in the container into said container and being further adapted to be raised out of said container so that said container may be moved sideways on said base, and mass equalizing means carried 50 by said base and connected to said compartment, said mass equalizing means being adapted to contribute to the support of said compartment so as to aid in the raising and lowering of said inlet member supported by said compartment.

- 60 16. A device for dispensing fluid from a container through an opening in the top of the container comprising, in combination, a compartment for accommodating said container, a base for said compartment, said base being adapted to support said container within said compartment, a pump supported by said compartment, the said pump having an inlet member extending downwardly into said compartment and being adapted 65 to be lowered through the opening in the top of the container into said container and being further adapted to be raised out of said container so that said container may be moved sideways on said base in and out from said compartment, 70 an upright member secured to said base and ex-

tending upwardly from said base, means for slidably engaging said compartment to said upright member, and counter-weight means carried by said base, said counter-weight means being adapted to contribute to the support of said compartment so as to aid in raising and lowering of said inlet member supported by said compartment engaged to the upright member.

- 5 17. A device for dispensing fluid from a container through an opening in the top of the container comprising, in combination, a compartment for accommodating said container, a base for said compartment, said base being adapted to support said container within said compartment, a pump supported by said compartment, 10 the said pump having an inlet member extending downwardly into said compartment and being adapted to be lowered through the opening in the top of the container into said container and being further adapted to be raised out of said 15 container so that said container may be moved sideways on said base in and out from said compartment, an upright member secured to said base and extending upwardly through said compartment, means for slidably engaging said compartment to said upright member so as to slide longitudinally of said upright member, and counter-weight means carried by said base, said counter-weight means adapted to contribute to the support of said compartment so as to aid in 20 raising and lowering of said inlet member supported by said compartment engaged to the upright member.

- 25 18. A device for dispensing fluid from a container through an opening in the top of the container comprising, in combination, a compartment for accommodating said container, a base for said compartment, said base being adapted to support said container within said compartment, a pump supported by said compartment, 30 the said pump having an inlet member extending downwardly into said compartment and being adapted to be lowered through the opening in the top of the container into said container and being further adapted to be raised out of said 35 container so that said container may be moved sideways on said base in and out from said compartment, an upright member secured to said base for guiding said compartment, means for slidably engaging said compartment to said upright member so as to slide longitudinally of said upright member, and counter-weight means carried by said base for aiding the longitudinal sliding movement of said compartment along said upright member.

- 40 19. The combination of a support for a container of fluid, said container having an opening in its top for the removal of the fluid, a pump for removing said fluid, said pump having an inlet member for inserting through said opening 45 into the container, means mounted upon said support for supporting said pump over the container, means carried by said support for lowering and raising the pump so that the said inlet member is inserted into or withdrawn from said 50 container, and guide means for guiding the movement of said inlet member.

- 55 20. A dispensing device for holding a container of fluid and dispensing said fluid through an opening in the top of the container comprising, 60 in combination, a compartment for holding said container, said compartment having a passageway on its side for the insertion and removal of the container in the compartment, a pumping device for withdrawing the fluid from the con- 65 70 75

- tainer, a conduit carried by said compartment, said conduit being in communication with said pumping device and adapted to be inserted into operative position within the opening in the 5 top of the container for pumping the said fluid therefrom and further adapted to be removed from its operative position within the container so that the container may be moved through the passageway in the side of said compartment 10 and mass equalizing means carried by said compartment for aiding in the raising of said conduit so that said conduit may be raised into inoperative position and lowered into operative position with a minimum of auxiliary effort.
- 15 21. A dispensing device for holding a container of fluid and dispensing said fluid through an opening in the top of the container comprising, in combination, a standard for holding said container, said standard being adapted to permit 20 the insertion and removal of the container from the standard through a side of the standard, a pump for withdrawing the fluid in the container, said pump having a longitudinal portion carried by said standard, said longitudinal portion 25 being in communication with said pump and adapted to be inserted into operative position within the opening in the top of the container for pumping the fluid therefrom and further adapted to be withdrawn from its operative position within the container so that the container 30 may be moved through the side of said standard, and mass equalizing means carried by said standard for aiding in the raising of said longitudinal portion of the pump so that said longitudinal portion may be raised into inoperative position 35 and lowered into operative position with a minimum of auxiliary effort.
22. A cabinet for a container, said container having an opening in its top, comprising, in combination, a base for supporting said container, a wall member carried by said base for embracing said container, a movable door mounted on the side of said wall member, said door being adapted to be opened and closed so that said container 40 may be moved through the side of said cabinet, a top cover for said wall member, said top cover having a downward extending flange adapted to extend down over the top of said wall member and door, the said top cover being adapted to be 45 moved relative to the opening in said container and to be raised relative to said wall member and door.
23. A cabinet for a container, said container having an opening in its top, comprising, in combination, a base for supporting said container, a side member extending from and carried by said base, said cabinet having a side through 50 which the container may be moved, a top cover carried by said side member for closing the top of said cabinet, said top cover having a downwardly extending flange protruding over the edge of said side member and bracing said side member, said cover having an opening, and a conduit extending through the opening in said cover, 55 said conduit being adapted to conduct fluid through the opening in said cover.
24. A cabinet for a container, said container having an opening in its top through which fluid passes, comprising, in combination, a base for 60 supporting said container, a side member having three sides secured to and extending upwardly from said base, said cabinet having an open side through which the container may be moved, a door member adapted to engage said side member and to close said open side, brace members 65
- extending from one of said sides to the other of said sides, a top cover having edge portions adapted to overlap and embrace said sides and said door member, the said cover having an opening, said opening being adapted to receive a conduit for said fluid.
25. A cabinet for a container, said container having an opening in its top, comprising, in combination, a raised platform for supporting said container, a side member adapted to partially surround said container, a movable door member adapted to engage said side member and to form with said side member an enclosure for said container, a top cover carried by said side member, 10 said top cover having a beveled peripheral portion and downwardly extending portion adapted to extend over and embrace said side member and door member, said cover having an opening, a pump mounted on said cover, said pump having an inlet member, said inlet member being adapted 15 to extend from said pump through the opening in the cover to said container, and an elongated guide member extending between the sides of said side member below said cover, said elongated guide member being adapted to guide and maintain said inlet member in vertical position.
26. A cabinet for a container, said container having an opening in its top, comprising, in combination, a base for supporting said container, a side member extending upwardly from and carried by said base, a top member extending between the sides of and carried by said side member, said top member having an open guide space therein, a conduit slidably engaged in said open 20 guide space and adapted to freely move in a vertical direction in said open space, and means carried by said top member and adapted to engage said conduit for holding said conduit in a desired 25 elevation relative to the said top member.
27. A cabinet for a container, said container having an opening in its top through which fluid passes, comprising, in combination, a rectangular platform for supporting said container, sump means on said raised platform for collecting contents of said container deposited on said platform, slide members mounted on said platform for facilitating the sliding of said container on said platform, a side member supported on and fastened to said platform, the said side member being formed of sheet metal bent to form an 30 enclosure on three sides of said platform, a door member adapted to engage said side member and to form an enclosure on the fourth side of said platform so that the said container may be enclosed on said platform by said side member and said door member, a top cover movably mounted on said side member, said top cover extending across the top of and over-lapping the sides of 35 said side member for bracing the said side member, said cover having a hole extending therethrough, said hole being adapted to receive a conduit for said fluid.
28. A holding member for a container, said container having an opening through which fluid passes in its top, comprising, in combination, a base for supporting said container, a side member supported upon and secured to the top of said base, said side member being formed of a piece 40 of sheet metal and having three sides, a door member formed of sheet metal and engageable with said side member to form an enclosure on said base for said container, the said door member being adapted to permit the removal of said container from said base, a top member carried 45
- 50
- 55
- 60
- 65
- 70
- 75

by said side member, the said top member having over-hanging edge portions adapted to engage sides of said side member and to brace said side member, the said top member having an open space therein through which the said fluid passes.

29. The combination of a support for a container of fluid, said container having an opening in the top of the container, the said support having a side member and a base and having a side through which the container may be moved, a pumping device carried by the said support for removing the fluid in the container, said pumping device having an inlet member adapted to be lowered through the opening in the top of the container into operative position in the said container and adapted to be raised up from the opening in the container out of operative position so that the said container may be moved sideways through the side of the support, and lift equalizing means for counter-balancing part of the weight of said inlet member so that said inlet member may be raised and lowered through the opening in the top of the container with a minimum of auxiliary effort when the said container is moved in and out of its position on the support, the said lift equalizing means being mounted on said side member.

30. The combination of a support for a container of fluid, said container having an opening in the top of the container, the said support having a side member and a base and having a side through which the container may be moved, a pumping device carried by the said support for removing the fluid in the container, said pumping device having an inlet member adapted to be lowered through the opening in the top of the container into operative position in the said container and adapted to be raised up from the opening in the container out of operative position so that the said container may be moved sideways through the side of the support, and lift equalizing means for counter-balancing part of the weight of said inlet member so that said inlet member may be raised and lowered through the opening in the top of the container with a minimum of auxiliary effort when the said container is moved in and out of its position on the support, the said lift equalizing means being mounted within said support.

31. The combination of a support for a container of fluid, said container having an opening in its top for the removal of the fluid, a pump for removing said fluid, said pump having an inlet member for inserting through said opening into the container, means for supporting said pump over the container, raising means for raising the pump so that said inlet member is withdrawn from the container, and weight equalizing means carried by said support for aiding said raising means in raising the pump.

32. The combination of a support for a container of fluid, said container having an opening in its top for the removal of the fluid, a pump for removing said fluid, said pump having an inlet member for inserting through said opening into the container, means carried by said support for supporting said pump over the container, raising means carried by said support for raising the pump so that said inlet member is withdrawn from the container, and weight equalizing means carried by said support for assisting said raising means.

33. A device for dispensing fluid from a container through an opening in the top of the con-

tainer comprising, in combination, a holding member for accommodating said container, said holding member having a side portion through which the container may be moved, a top cover for said holding member, a pump mounted on said cover, the said pump having an inlet member extending through the said cover and adapted to be inserted through the opening of the container into said container, a supporting rod attached to said cover and slidably engaged to the holding member, spring tension means, a portion of said tension means being anchored to said holding member, and connecting means between said supporting rod and said spring tension means, the combination of the holding member, the pump, and the spring tension means being such that the inlet member of the pump may be lowered and raised in respect to said container with the aid of said spring tension means and so as to permit the container to be moved through the side of the holding member by raising the inlet member out of the opening in the container.

34. A device for dispensing fluid from a container through an opening in the top of the container comprising, in combination, a holding member for accommodating said container, said holding member having a side portion through which the container may be moved, a top cover for said holding member, a pump mounted on said cover, the said pump having an inlet member extending through the said cover and adapted to be inserted through the opening of the container into said container, supporting means for said pump and inlet member, spring tension means carried by said holding member, a portion of said tension means being anchored to said holding member and connecting means between said supporting means and said spring tension means, the combination of the holding member, the pump, and the spring tension means being such that the inlet member of the pump may be lowered and raised in respect to said container with the aid of said tension means and so as to permit the container to be moved through the side of the holding member by raising the inlet member out of the opening in the container.

35. A device for dispensing fluid from a container through an opening in the top of the container comprising, in combination, a holding member for accommodating said container, said holding member having a side portion through which the container may be moved, a top cover for said holding member, a pump mounted on said cover, the said pump having an inlet member extending through the said cover and adapted to be inserted through the opening of the container into said container, supporting means for said pump and inlet member, a coil spring mounted transversely of said holding member and having one end anchored to said holding member, a cable connecting the other end of said spring to the said supporting means, a reel for said cable, said reel being carried by said holding member, said spring and cable being adapted to contribute toward the support of said supporting means, the combination of the holding member, the pump, and the spring being such that the inlet member of the pump may be lowered and raised in respect to said container with the aid of said coil spring and so as to permit the container to be moved through the side of the holding member by raising the inlet member out of the opening in the container.

36. A device for dispensing fluid from a con-

5 tainer through an opening in the top of the container comprising, in combination, a holding member for accommodating said container, said holding member having a side portion through which the container may be moved, a top cover for said holding member, a pump mounted over said cover, the said pump having an inlet member extending through the said cover and adapted to be inserted through the opening of the container into said container, a supporting rod for 10 supporting said pump and inlet member, said supporting rod being slidably engaged to said holding member, lift equalizing means mounted on said holding member, connecting means between said lift equalizing means and said supporting rod, the said lift equalizing means being adapted to contribute to the support of said pump and inlet member so as to aid in the withdrawal of said inlet member from the opening in the top of 15 the container, and locking means carried by the said holding member for restraining the vertical movement of the said inlet member relative to said holding member.

37. A device for dispensing fluid from a container through an opening, in the top of the container comprising, in combination, a holding member for accommodating said container, said holding member having a side portion through which the container may be moved, a top cover for said holding member, a pump mounted over said cover, the said pump having an inlet member extending through the said cover and adapted to be inserted through the opening of the container into said container, a supporting rod for supporting said pump and inlet member, said supporting rod being slidably engaged to said holding member, lift equalizing means mounted on said holding member, connecting means between said lift equalizing means and said supporting rod, the 40 said lift equalizing means being adapted to contribute to the support of said pump and inlet member so as to aid in the withdrawal of said inlet member from the opening in the top of the container, movable stop means for locking said supporting rod against movement relative to said holding member, and means for moving said movable stop means.

38. A device for dispensing fluid from a container through an opening in the top of the container comprising in combination, a holding member for accommodating said container, said holding member having a side portion through which said container may be moved, a top cover for said holding member, a pump supported by said holding member, the said pump having an inlet member extending downwardly and adapted to be inserted through the opening of the container into said container, the said inlet member being adapted to be raised out of said container 50 so that the container may be moved through the side portion of said holding member and adapted to be lowered into said container so that the fluid therein may be removed, and a horizontal member mounted below said cover to said holding member, said horizontal member being adapted to hold said inlet member in upright position when withdrawn from said container.

39. A device for dispensing fluid from a container through an opening in the top of the container comprising, in combination, a holding member for accommodating said container, said holding member having a side portion through which said container may be moved, a top cover for said holding member, a pump supported by 55 said holding member, the said pump having an

inlet member extending downwardly through said cover and adapted to be inserted through the opening of the container into said container, rack and pinion means carried by said holding member for raising and lowering said inlet member relative 5 to the said container, and guide means for stabilizing the raising and lowering movement of the inlet member.

40. A device for dispensing fluid from a container through an opening in the top of the container comprising, in combination, a holding member for accommodating said container, said holding member having a side portion through which said container may be moved, a top cover for said holding member, a pump supported by 10 said holding member, the said pump having an inlet member extending through said cover and adapted to be inserted through the opening of the container into said container, spring tension means mounted to said holding member, a pulley 15 mounted upon and responsive to said tension means, flexible connecting means connecting said pulley and said inlet member so that the action of the spring tension means contributes to the support of said inlet member and aids in the 20 raising of the inlet member out of the opening in the top of the container, a guide member slidably engaging said inlet member for guiding its movement, and means for locking said inlet member to said guide member. 30

41. A device for dispensing fluid from a container through an opening in the top of the container comprising, in combination, a holding member for accommodating said container, said holding member having a side portion through which said container may be moved, a top cover for said holding member, a pump supported by 35 said holding member, the said pump having an inlet member extending through said cover and adapted to be inserted through the opening of the container into said container, and a coil spring mounted transversely of and within said holding member, said coil spring having one end anchored to the holding member and the other end anchored to the said inlet member and adapted to exert an upward force upon said inlet member. 40

42. In combination, housing means for a container having an opening in its top, said housing means having side wall means arranged to be 50 raised and lowered relative to the container, a dispensing member through which fluid may be dispensed from the container, means for supporting the dispensing member in a downward position within the housing means and at a distance from the said side wall means and causing it to extend into the container through the said opening in the top thereof, and means for raising the dispensing member and the side wall means 55 to cause both to clear the container to facilitate the sideward insertion and removal of the container into and from the housing means. 60

43. In combination, housing means for a container having an opening in its top, said housing means having side wall means through which the container may be inserted or withdrawn sideways into and from the housing means, a dispensing member through which fluid may be dispensed from the container, means for supporting the dispensing member in a downward position within 70 the housing means and at a distance from the said side wall means and causing it to extend into the container through the said opening in the top thereof, and means for raising the dispensing member to cause it to clear the container to 75

facilitate the sideward insertion and removal of the container into and from the housing means.

44. In combination, housing means for a container having an opening in its top, said housing having side wall means, a dispensing member through which fluid may be dispensed from the container, means for supporting the dispensing member in a downward position within the housing means and at a distance from the side wall means and causing it to extend into the container through the said opening in the top thereof, a

plurality of spaced means for raising the dispensing member to cause it to clear the container to facilitate the sideward insertion and removal of the container into and from a position under the dispensing member, and means for causing the said spaced means to move substantially synchronously and evenly to distribute the load upon the said spaced means.
